ATTORNEYS

UNITED STATES PATENT OFFICE.

RAWLEY DE WITT HAAS, OF LA HABRA, CALIFORNIA.

PLAYING CARDS.

Application filed October 29, 1921. Serial No. 511,283.

To all whom it may concern:

Be it known that I, RAWLEY DE WITT HAAS, a citizen of the United States, and a resident of La Habra, in the county of Los Angeles and State of California, have invented certain new and useful Improvements in Playing Cards, of which the following is a specification.

My present invention relates particularly to playing cards, my object being the provision of playing cards by means of which various games may be played including practically all games to which the ordinary playing cards are adapted, as well as many others.

While differing materially in certain respects from the usual playing cards, my improved set of cards while adapted to the playing of many interesting games beyond those of which the ordinary playing cards are adapted, are in many respects similar to the usual playing cards and are sufficiently like the latter so that practically all games of which the ordinary playing cards are capable, can be played with the improved cards. This is an important consideration of the invention and like the points of difference over the ordinary cards, may be readily understood and appreciated from the following description with reference to the accompanying drawing, which forms a part of this specification and in which,

Figures 1 to 9 inclusive are face views of different cards of the set, illustrative of the various suits and the card corresponding to the joker card of the usual playing cards as hereinafter mentioned.

My invention proposes a set of playing cards which like the usual playing cards includes four suits, the four suits being in the present instance however, distinguished by geometrical figures and colors. Two suits are of one color and two suits are of another color, the suits of one color having different geometrical figures and the suits of the other color having different geometrical figures corresponding in reversed relation to the geometrical figures distinguishing the suits of the first mentioned color. Thus there are two red suits, one suit being red dot and the other red square and there are two black suits, one black dot and one black square.

Figures 1 and 2 show the highest and next to the highest cards of the red dot suit, each card of this suit having a large red

circle 10 in which the main value of the card is determined by the letter or numeral 11 appearing in the circle 10. This main numeral or letter is duplicated in small size at 12 at diagonally opposite corners of the card accompanied by a miniature 13 of its central figure 10 as well as a letter or numeral 14 located inwardly beyond the miniature 13 of its central figure.

Each suit consists of sixteen cards ranging from 3 to 18, Figures 1 and 2 showing cards A and B of the red dot suit, these cards being numbers 18 and 17 of that particular suit; Figures 3 and 4 showing cards C and D of the black dot suit, being cards 16 and 15 of that particular suit; Figures 5 and 6 showing cards J and 10, being cards 11 and 10 of the red square suit, and Figures 7 and 8 showing cards 9 and 3 of the black dot suit. Figure 9 shows the square dot card, equivalent to the joker of the usual playing cards, having in addition to its designations as the square dot card a large red circle 15 within a black square 16.

The cards from 3 to 10 of each suit have their main designations within their central figures in the form of numerals progressing from 3 to 10 inclusive, the 10 card shown in Figure 6 being the highest card of the numeral series and the 3 card shown in Figure 8 being the lowest card of the numeral series. Each numeral card has its main designating numeral 17 duplicated in diagonally opposite corners outwardly beyond the miniature 13 as at 18 and each numeral card has its corresponding letter value in a small letter 19 inwardly beyond the miniature 13, there being an equal number of numeral and letter cards in each series so that the numeral cards may have small letters 19 in their pips corresponding to the large letters of the letter series A, B, C, D, E, F, G and J in the order named. Thus the 10 card of the numeral series of each suit will have the small letter A, the 9 card will have the small letter B, the 8 card will have the small letter C, the 7 card will have the small letter D, the 6 card will have the small letter E, the 5 card will have the small letter F, the 4 card will have the small letter G and the 3 card will have the small letter J, it being understood that these letters, however small, will preferably be capital letters as shown in Figures 6, 7 and 8.

The letter series of each suit, including the eight cards A, B, C, D, E, F, G, J have their

numerals 14 inwardly beyond the miniature figures in their pips individually corresponding to their values in the suit, the A card having the small numeral 18, the B card 5 having the numeral 17, the C card having the numeral 16, the D card having the numeral 15, the E card having the numeral 14, the F card having the numeral 13, the G card having the numeral 12 and the J card 10 having the numeral 11, and it is thus obvious the cards of each series may be played as if progressing from 3 to 18 without any reference whatever to the letter series above the 10 card, likewise each suit may be played as 15 if the two series were entirely independent, that is by disregarding altogether the numerals of the letter cards above the 10 card.

Likewise the square dot card of Figure 9 may be played as the highest card of both 20 the numeral and letter series of the trump suit or it may be utilized as the highest card of merely the numeral series of the trump suit having a value below the letter series of that suit.

25 Moreover the trump may be declared as either red dot, red square, black dot or black square, that is designating the entire suit as trump including both the numeral and letter cards, or the trump may be declared as the letter cards of any series or the 30 numeral cards of any series, the other series not so named being either played as sub-trump cards with a value proportionately less than that of the cards declared as trump, 35 or as non-trump cards having no value and played like the cards of the other suits.

There being sixteen cards to each complete suit and four suits, the entire set of cards will total sixty-four in number with the 40 square dot card of Figure 9 making the sixty-fifth card, and it is quite obvious that by distinguishing the different suits as I have done by two colors and two figures, the suits of like color having different figures 45 and the suits of like figures having different colors, it is obvious that the entire set of cards are thus divided in half by specifying the figures without reference to the colors or by specifying the colors without reference to the figures. Thus the trump may be declared either dots or squares. If declared squares, the black squares and red squares 50 are played against the black dots and red dots. If however the trump is declared red,

the red dots and red squares will be played 55 against the black dots and black squares.

The entire set may thus be divided readily into halves as just described, into fourths as by designating each suit complete that is red dots, red squares, black dots and black 60 squares, and may also be divided into eighths as where either the letter series or the numeral series of any particular suit is selected in the manner previously set forth.

In using the cards proposed by my invention it will be found that substantially all of the games capable of being played by the usual cards may with equal facility be played with my cards and in addition to such games, many others of similar or 70 greater interest and entertainment may be played with my cards of which the ordinary cards are incapable.

I claim:

1. A set of playing cards consisting of 75 four suits of sixteen cards each, one pair of suits having one color and the other pair having another color, one suit of each color having the same figure designation and the other suit of each color having the same figure designation different from the figure of the first two pairs, each of said suits being divided into two series of eight cards each, one series including numeral cards of progressively increasing numbers and the other series having letter cards each with a different letter.

2. A set of playing cards consisting of 80 four suits of sixteen cards each, one pair of suits having one color and the other pair having another color, one suit of each color having the same figure designation and the other suit of each color having the same figure designation different from the figure of the first two pairs, each of said suits being 85 divided into two series of eight cards each, one series including numeral cards of progressively increasing numbers and the other series having letter cards each with a different letter, the cards of the numeral series of 90 each suit having letter pips corresponding to the letters of the cards of the letter series, and the cards of the letter series having 95 numeral pips progressively increasing above the numerals of the cards of the numeral 100 series.

RAWLEY DE WITT HAAS.
